UNITED STATES PATENT OFFICE.

WESLEY E. COCHRAN, OF CLEVELAND, OHIO.

LIGHTING-FIXTURE.

1,292,432.

Specification of Letters Patent.

Patented Jan. 28, 1919.

Application filed May 2, 1918. Serial No. 231,997.

To all whom it may concern:

Be it known that I, WESLEY E. COCHRAN, a citizen of the United States, residing at Cleveland, in the county of Cuyahoga and State of Ohio, have invented certain new and useful Improvements in Lighting-Fixtures, of which the following is a specification.

My invention relates to improvements in lighting fixtures, the primary object of the invention being to provide a generally improved fixture of this class which will be exceedingly simple in construction, cheap of manufacture, and efficient in use.

A further object is the provision of a fixture which will provide a field of illumination of great uniformity throughout, and particularly free of glare, shadows and other objectionable features.

A still further object is the provision of an improved fixture of this class particularly designed and adapted for use in connection with a lamp bulb of the "nitrogen type" now in extensive use, and which not only gives very intense light at its filament, but has an elongated bulb stem or shank, and with this end in view my invention further relates to an improved non-transparent canopy extending above the light source and a translucent or light diffusing shade carried by and closing the lower end of said reflector, and provided with an opening receiving and containing said bulb.

A still further object is the provision of improved means for attaching and mounting the improved parts in connection with any standard or conventional forms of lamp sockets and incandescent lamp bulbs.

A still further object is the provision of an improved fixture of this class, which is adapted not only to provide for proper circulation of air about the lamp bulb to cool and prolong the life of the latter, but one which is particularly sanitary and safe in use, being particularly free from dust-collecting openings or pockets, and at the same time presenting an ornamental and attractive outline and artistic appearance.

With the above mentioned and other ends in view, the invention consists in the novel construction, arrangement, and combination of parts, hereinafter described, illustrated in some of its embodiments in the accompanying drawings, and particularly pointed out in the appended claims.

Referring to the drawings, forming a part

of this specification, Figure 1, is a side elevation of a lighting fixture constructed in accordance with this invention and embodying a lamp socket of conventional form and an electric lamp bulb of the "nitrogen type".

Fig. 2, a central vertical sectional view of the improved canopy and shade, and illustrating a modified form of means for attaching and connecting the canopy to another form of lamp socket.

Fig. 3, a side elevation of a lighting fixture embodying a further modification, in which the canopy reflector is detachably mounted upon the neck of the lamp bulb instead of the lamp socket.

Fig. 4, a vertical central sectional view of the canopy reflector and light diffusing shade, the lamp bulb being detached from the socket.

Similar numerals of reference designate like parts throughout all the figures of the drawings.

The improved lighting fixture is shown in connection with a lamp socket 1, of the conventional form, and the improved canopy reflector 2, is preferably detachably mounted upon and connected to the lamp socket, as shown in Figs. 1, and 2 of the drawings, said means of connecting and mounting, in the present instance, embodying inwardly extending projections adapted to slip over and interlock with the usual outwardly extending conventional projections, such for example, as the flange or beading 1^a, shown in Figs. 1 and 3, of the drawings, or the outwardly extending or projecting thread beadings 1^b, as shown in Fig. 2 of the drawings. The inwardly extending projections, in the present instance, are in the specific form of inwardly extending studs or projections 2^a, adapted to slip over and interlock with the beading 1^a, as shown in Fig. 1, of the drawings, there being sufficient looseness of fit and resiliency in the neck portion of the canopy reflector, in this instance, to permit of the interlocking action in the attachment or detachment of the canopy reflector, or where the lamp socket 1, is provided with thread beadings 1^b, of conventional form, as shown in Fig. 2, of the drawings, such inwardly extending projections may be in the form of thread beadings 2^b, adapted to thread over and to register with the projecting thread beading 1^b, as shown.

The lamp socket 1, is provided, in the

- present instance, with a lamp bulb 3, of the nitrogen type, and which therefore embodies a long or elongated neck portion 3^a, and a filament 3^b.
- 5 If desired, the canopy reflector 2, and the improved diffusing shade carried thereby, as hereinafter described, may be initially attached to the lamp bulb, as shown in Fig. 4, of the drawings, and before the bulb is 10 assembled and screwed into the lamp socket, as shown in Fig. 3, of the drawings, and for this purpose the neck portion of the canopy reflector 2, is provided with an inwardly extending projection, in the specific form of 15 an inwardly extending flange 2^c, adapted to rest upon and interlock with the shoulder portion 3^e, of the neck portion 3^a, of the lamp bulb. The lamp bulb, in the present instance, is provided with the usual light 20 diffusing portion 3^d, of the conventional "sand blasted" form, said light diffusing or translucent shade portion 3^d, extending below the horizontal median portion 3^e, or in other words,—on a horizontal plane common 25 to the horizontal plane of the filament 3^b, and at right angles to the longitudinal axis of the latter and the lamp bulb.
- As a means of intercepting and diffusing the direct and reflected rays from the light 30 source 3^b, and canopy reflector 2, respectively, of all rays of light not intercepted by the light diffusing or shaded portion 3^d, of the lamp bulb, the canopy reflector 2, is provided with a light diffusing or translucent shade 4, carried by and closing the lower end of the canopy reflector 2, said light 35 diffusing shade 4, being provided with a central opening 4^a, receiving and containing the bulb 3, said light diffusing or translucent 40 shade being preferably bowl-shaped, as shown, and extending from and above the horizontal median portion 3^e. It will be seen that the lower edge of the light diffusing or translucent shade 4, is arranged on a horizontal 45 plane substantially coincident with the horizontal plane or median portion 3^e, of the filament 3^b, and at right angles to the longitudinal axis of the lamp bulb, and the translucent shade not only closes the lower 50 end of the canopy reflector 2, and bridges the space between the lower edges of the latter and the upper edge 3^e, of the light diffusing portion 3^d, but conjointly with the latter forms a translucent or light diffusing 55 shade, as a whole, extending entirely around and beneath the light source and below the canopy reflector to intercept and diffuse all direct and reflected rays from the light source and canopy.
- 60 The canopy 2, may be of any suitable and convenient form, but is preferably made of non-transparent material with a light reflecting or polished interior surface to form a reflector, and the marginal edges of the 65 canopy 2, and light diffusing or translucent

shade 4, may be connected in any suitable and convenient manner, as for example, by means of a marginal flange or beading 2^d, as shown in the drawings.

The lower edges 4^a, of the shade are preferably slightly spaced from the lamp bulb 3, to provide an air circulating space 4^b, and, if desired, the neck portion of the canopy may be provided with a plurality of openings 4^c, for a similar purpose. 70 75

From the foregoing description, taken in connection with the accompanying drawings, the operation and advantages of my invention will be readily understood.

Having thus described some of the embodiments of my invention, what I claim and desire to secure by Letters Patent is,—

1. A lighting fixture, comprising an electric lamp bulb, a socket having external projections, a bell-shaped canopy reflector having a neck extending over said socket and interlocking with said projections, and a light diffusing shade carried by and closing the lower end of said reflector and provided with an opening receiving and containing 90 said bulb. 85

2. A lighting fixture, comprising a light source and a bulb having a light diffusing section beneath the latter, a canopy extending above said light source and having its lower edge spaced above the horizontal plane of the upper edge of said light diffusing section, and a translucent shade carried by and closing the lower end of said canopy and having a central opening receiving said bulb light diffusing section and extending from and above the latter. 95 100

3. A lighting fixture, comprising a lamp socket provided with beaded projections, a lamp bulb mounted in said socket, a canopy reflector having a ventilated neck provided with internal projections seated on and interlocking with said beaded projections, and a light diffusing shade carried by and closing the lower end of said canopy reflector and having a central opening containing 110 said bulb. 105

4. A lighting fixture, comprising an electric lamp bulb including an elongated neck and a filament, a lamp socket, a canopy reflector surrounding said neck detachably connected to said socket and terminating above said bulb, and a bowl-shaped shade carried by and closing the lower end of said canopy reflector and having a central opening receiving and surrounding said bulb on a horizontal plane passing through said filament. 115 120

5. A lighting fixture, comprising an electric lamp bulb including a neck and a light diffusing portion on said bulb below the horizontal median portion, a lamp socket, a canopy reflector carried by said socket and surrounding said neck, and a light diffusing shade carried by and closing the lower end 125 130

- of said reflector and provided with an opening containing said bulb and covering said bulb above said light diffusing portion thereof.
- 5 6. A lighting fixture, comprising a bulb including a light source and a light diffusing section extending from the horizontal plane common to said light source and at right angles to the longitudinal axis of said bulb, a canopy surrounding the upper portion of said bulb and having its lower edge spaced above said light diffusing section, and a translucent shade carried by and closing the lower end of said canopy and having
- 10 15 an opening receiving said bulb and having its lower edge arranged coincident with the horizontal plane of said light source and bridging the space between said light diffusing section and said canopy.
- 15 20 7. A lighting fixture, comprising a lamp bulb including an elongated neck and a light source therein, said bulb having a light diffusing semi-spherical section extending beneath a horizontal plane common to said
- 20 25 light source and at right angles to the longitudinal axis of said bulb, a canopy surrounding the elongated neck portion of said bulb and having its lower edge spaced above said light diffusing semi-spherical section, and a translucent shade carried by and closing 30 said canopy and having an opening receiving said bulb and arranged coincident with said horizontal plane of said light source and bridging the space between said light diffusing section and said canopy.
- 35 8. A lighting fixture, comprising an electric lamp bulb having a light diffusing semi-spherical section extending from a horizontal plane coincident with the horizontal plane of its filament and at right angles to the longitudinal axis thereof, a canopy reflector surrounding said bulb and spaced above said light diffusing section, and a translucent shade closing the lower end of said canopy reflector and having an opening 40 extending in said horizontal plane and receiving said light diffusing section and forming conjointly therewith a translucent shade extending from the lower edges of said canopy reflector and beneath the light 45 source of said bulb.
- 45 50 In testimony whereof I have affixed my signature in the presence of two witnesses.
